AUTOMATIC BACKWATER VALVE

Fred B. Mingus and Walter R. Meyer,
Oshkosh, Wis.

Application July 23, 1935, Serial No. 32,792

6 Claims. (Cl. 182—25)

This invention relates to an automatic backwater valve, and has for its principal object the production of a simple and efficient automatic valve mechanism which is especially adapted to be mounted within the hub or bell of a basement drain without the necessity of changing the construction of the drain in the basement.

Another object of this invention is the production of a simple and efficient valve mechanism which is designed particularly for mounting within a drain pipe to prevent the backflow of water through the drain, special means being provided to insure the closing of the valve and also to hold the float in its proper vertical position.

Other objects and advantages of the present invention will appear throughout the following specification and claims.

In the drawing:

Figure 1 is a vertical sectional view through a drain pipe showing the improved automatic backwater valve in an open position;

Figure 2 is a vertical section taken through a drain pipe showing the valve mechanism in a closed position;

Figure 3 is a transverse sectional view taken on line 3—3 of Figure 2; and

Figure 4 is a vertical section through the hinge portion of the valve showing the means for regulating the tension upon the valve.

By referring to the drawing, it will be seen that D designates a drain which may be of any suitable or desired type of construction without departing from the spirit of the invention. The drain D is provided with the conventional shoulder S near its upper end, and carries a closure grate or perforated plate P of the usual type of construction.

The present invention embodies principally a surface plate or top plate 10 preferably of a disc-like structure having an upwardly extending inwardly inclined flange 11 upon its periphery, the plate 10 being adapted to rest upon the supporting ring R which in turn rests upon the shoulder S of the drain pipe D. This top plate 10 is also provided with a centrally located opening 12 around the edge of which is formed a depending annular flange 13 which will constitute a valve seat for the valve 14 or sealing disc 19. The flange 11 is inclined inwardly to facilitate corking, as indicated at 11a.

Suspending bolts 15 are secured to the plate 10 to one side of the opening 12, as shown in Figure 1, and these suspending bolts 15 carry a spacing block 16 upon which rests a hinge plate 17. The hinge plate 17 is interposed between the bottom face of the plate 10 and the upper face of the block 16. A hinge plate 18 is secured to the bottom face of the block 16, as shown in Figure 1, and is anchored in position by the bolts 15. The hinge arm 14 is hingedly connected to

the hinge plate 17, as shown in the drawing, and this hinge arm 14 carries a valve or sealing disc 19 upon its upper face, which valve 19 may be of any suitable or desired nature to provide a sealing and water-tight fit upon the lower edge 15 of the flange 13 when the valve 19 is moved to a closed position, such as is shown in Figure 2.

The hinge arm 14 is provided near its outer end with a depending knuckle 23 to which is hingedly secured, as at 24, the depending float supporting pendulum rod 25, which rod 25 carries the cork or other similar float 26 at its lower end. The float 26 is adjustable upon the lower threaded end of the rod 25. The rod 25 extends through an apertured plate 22 which is locked in position above the float 26 by means of the lock nuts 21. A hinge knuckle 20 is hingedly connected to the hinge plate 18 and a threaded rod 27 is secured to the knuckle 26, as shown in Figure 4. This threaded rod 27 is provided with a reduced 20 extension 28 which is threaded into the yoke 29. The yoke 29 is pivotally connected to the float supporting rod 25 by means of a pin 30. A coil spring 31 is connected at one end to the apertured plate 22, and at its opposite end to an adjustable hanger plate 32. The hanger plate 32 is provided with an aperture 33 through which the threaded rod 27 extends, as shown in Figure 4.

The valve 19 will normally hang in the position shown in Figure 1, to allow the opening 12 to remain open and it should be noted that all of the operating parts of the valve are mounted upon the under face of the valve, thereby protecting these operating parts and allowing a free 35 unobstructed flow of water through the opening 12. Consequently, the mechanism will be shielded and in a position to be protected against damage. Should a backflow of water occur, the float will ride upon the surface of the water 40 entering the trap or drain D, thereby swinging the valve 19 from the position shown in full lines in Figure 1 to the position shown in Figure 2. The weight of the valve, however, under normal conditions will be sufficient to hold the 45 valve in an open position but upon the entrance of a backflow of water the buoyancy of the float 26 will cause the valve 19 to raise to a closed position whereupon the spring 31 will assist in more tightly forcing the valve 19 to a closed position and thereby seal the entrance opening or valve seat 13.

By carefully considering Figure 4, it should be understood that the hanger plate 32 may be adjusted upon the length of the threaded rod 27 to 55 increase or decrease the tension of the spring 31 since by sliding the plate 32 upwardly upon the length of the rod 27, the tension of the spring 31 will be increased, thereby allowing the valve 19 to be normally held at a desired angle. Ordin- 60

narily, the rod 27 may be properly adjusted upon the yoke 29 when assembling the device, and the plate 32 will normally rest against the shoulder 34, as shown in Figure 4, but as stated above this 5 plate 32 may be adjusted to the position shown in dotted lines in Figure 4, to increase the tension of the spring and to hold the valve 19 in a more nearly closed position. Through the medium of this structure, a very simple and efficient tension 10 controlling device will be provided to regulate the angle which will be normally assumed by the valve 19. As soon as the buoyancy of the water tends to lift the float 26, the spring 21 will tend to snap the valve 19 to a closed position.

15 From the foregoing description, it will be seen that a very simple and efficient automatic back-water valve has been provided which is especially adapted for placing in sewer drains in basements, and the like, to act under all conditions and to 20 automatically close the opening in the drain to prevent the backwash of water through the drain. This device is especially adapted to prevent the backing up of the water in the sewer into the basement which would cause damage and loss to 25 the contents of the basement.

The device is especially adapted to be installed in the conventional hub or bell of the basement drain without changing the drain and it is not the purpose of this application to limit the structure to any particular type of drain structure. The plate P will shield the drain against the entrance of foreign material such as paper, chips, cigar or cigarette butts, and thereby protect the 30 valve 19.

35 It should be understood that certain detail changes in the mechanical construction, combination and arrangement of parts may be employed without departing from the spirit of the invention, so long as such changes fall within the 40 scope of the appended claims.

Having described the invention, what is claimed as new is:—

1. A device of the class described comprising a plate having an opening, and a valve seat formed 45 around the opening, a valve hingedly secured adjacent the opening and adapted to open and close the opening, a pendulum rod hingedly secured to said valve, a float carried by said pendulum rod, said pendulum rod connecting the float 50 to the valve, and means engaging said pendulum rod for holding the same in a substantially vertical position and preventing the swinging of the float back against the valve, the lifting action of water upon the float being adapted to force said 55 valve tightly upon its seat.

2. A device of the class described comprising a plate having an opening, and a valve seat formed around the opening, a valve hingedly secured adjacent the opening and adapted to open and close 60 the opening, a pendulum rod hingedly secured to said valve, a float carried by said pendulum rod, said pendulum rod connecting the float to the valve, and a hingedly mounted rod extending under said valve and engaging said pendulum rod for holding said pendulum rod in a substantially upright 65 position and preventing the pendulum rod and float from swinging back against the valve, the lifting action of water upon the float being adapted to force said valve.

3. A device of the class described comprising a 70 plate having an opening, and a valve seat formed around the opening, a valve hingedly secured ad-

jacent the opening and adapted to open and close the opening, a pendulum rod hingedly secured to said valve, a float carried by said pendulum rod, said pendulum rod connecting the float to the valve, a hingedly mounted rod extending under 5 said valve and engaging said pendulum rod for holding said pendulum rod in a substantially upright position and preventing the pendulum rod and float from swinging back against the valve, and spring means for assisting in holding the 10 valve in a closed position after said float is raised.

4. A device of the class described comprising a plate having an opening, and a valve seat formed around the opening, a valve hingedly secured adjacent the opening and adapted to open and close 15 the opening, a pendulum rod hingedly secured to said valve, a float carried by said pendulum rod, said pendulum rod connecting the float to the valve, a hingedly mounted rod extending under said valve and engaging said pendulum rod for 20 holding said pendulum rod in a substantially upright position and preventing the pendulum rod and float from swinging back against the valve, a spring engaging said rod and assisting in holding the valve in a closed position after said float 25 has been raised, a hanger plate, said spring being secured to said hanger plate, and said hanger plate being adjustable upon said hingedly mounted rod for regulating the tension of said spring and adjusting the normal angle at which said 30 valve extends when in an open position.

5. A device of the class described comprising a plate having an opening, and a valve seat formed around the opening, a valve hingedly secured adjacent the opening and adapted to open and close the opening, a float hingedly secured to the valve to insure a tight fit of the valve upon its seat, a pendulum rod hingedly secured to said valve, a float carried by said pendulum rod, said pendulum rod connecting the float to the valve, a hingedly mounted rod extending under said 35 valve and engaging said pendulum rod for holding said pendulum rod in a substantially upright position and preventing the pendulum rod and float from swinging back against the valve, a 40 spring engaging said rod and assisting in holding the valve in a closed position after said float has been raised, a hanger plate, said spring being secured to said hanger plate, said hanger plate being adjustable upon said hingedly mounted rod 45 for regulating the tension of said spring and adjusting the normal angle at which said valve extends when in an open position, said hanger plate having an aperture through which said hingedly mounted rod extends, and said hingedly mounted 50 rod being threaded whereby said hanger plate may be held in an adjusted position upon the length of said hingedly mounted rod.

6. A device of the class described comprising a support having an opening formed therein, a valve 60 hingedly secured adjacent said opening, a float, means hingedly suspending said float below said valve, and means engaging said last mentioned means for holding the last mentioned means and said float in a substantially vertical position 65 whereby liquid entering below and engaging said float will force said valve to a closed position over said opening.
